TAPE HANDLING APPARATUS

Joseph Ettl, Plainfield, N. J., assignor to Potdevin Machine Company, Brooklyn, N. Y., a corporation of New York

Application June 12, 1931, Serial No. 543,874

8 Claims. (Cl. 164—42)

This invention relates to an improvement in motor driven machines for dispensing paper tape, and has for one of its objects the provision of a machine adapted to feed the tape from a supply roll, cut it off as desired, apply adhesive to the severed portion and then to discharge the glued or pasted tape from the machine.

The machine is in part manually operated, that is to say, does not measure the paper and cut the same off after predetermined length has run through the machine.

In the drawings accompanying this application:

Fig. 1 is a view of my improved machine in part 15 section front elevation;

Fig. 2 is a section substantially on the line 2—2 of Fig. 1;

Fig. 3 is a section substantially on the line 3—3 of Fig. 1;

Fig. 4 is a view on the line 4—4 of Fig. 3;

Fig. 5 is an elevational view of part of the cutting off mechanism;

Fig. 6 is a fragmentary view of the knife mechanism;

Fig. 7 is a detail of certain clutch throw out mechanism; and

Fig. 8 is a detail of the slip clutch mechanism.

Referring to the drawings in detail, 1 and 2 designate the side frames of the machine. The 30 roll of paper designated 3 is supported on a bracket 4 mounted in any convenient manner on the machine frame, the tension on the tape being controlled by a pivoted arm 5 which carries a shoe 6 adapted to rest on the periphery of the 35 roll. The tensioning arm 5 is provided with a weight 7 adjustable lengthwise of the arm to vary the pressure on the tape roll 3. To hold the weight in any adjusted position the same is provided with a pin 8 backed by spring 9, the pin 40 engaging undulations 10 in the upper edge of the arm.

The tape, which I shall designate 11, passes from the roll 3 between a pair of feed rollers 12 and 13. The rollers are mounted on shafts 14 and 15, respectively, the shaft 14 being mounted in hinged frame members 14', the shaft 15 being mounted in the side frame 1 and 2 of the machine.

The bearings for the shaft 14 are backed by springs 16 whereby the pinch or nip of the rollers 12 and 50 13 on the tape may be regulated, a screw 17 being provided for varying the tension in the spring 16.

From the feed rolls 12 and 13 the paper passes along the upper face of a stationary cutter member 18 which will be described in detail later on, and from thence passes between another pair of

5 feed rollers 19 and 20 which are mounted on shafts 21 and 22, respectively, the shaft 21 being mounted in hinged frame members 14', and the shaft 22 in the side frames 1 and 2. The bearing for the roller 19 is backed by spring 23 so as to mount this roller resiliently.

The paper next goes over the top of a gluing roller 24 which is mounted on a shaft 25 mounted in suitable bearings in the frames of the machine, this roller receiving glue from the roller 26 which is mounted on shaft 27, in a glue tank 28.

The driving motor for the machine is designated 29. This motor is provided with a gear 30 meshing with a gear 31 on a shaft 32 carried in bearings 33, 34 and 35 along the side of the machine frame 1.

The shaft 32 carries a gear 36 meshing with a gear 37 loose on the shaft 15 of the feed roller 13.

The shaft 32 also carries a gear 38 meshing with a gear 39 on the shaft 22 which carries the feed roller 20.

The shaft 32 also carries a gear 40 meshing with a gear 41 on the shaft 25 which carries the gluing roller 24.

Pivoted on the frame of the machine is a cutter 25 bar 42 carrying a cutter blade 43. The end of this cutter bar opposite its pivot 44 has a spring 45 attached to it, this spring being anchored to a pin 46 fast to the machine frame. The opposite end of the cutter bar 42 is pivotally attached at 30 47 to a vertically movable yoke 48 to the rear face of which, as viewed in Fig. 4, is attached a bracket 49 adjustably held in place thereon by screws 50, this bracket having a portion 51 projecting away from the face of the member 48.

At its lower end the yoke 48 is cut away as shown at 52 to receive a collar 53 mounted on a shaft 54, the shaft being mounted in suitable bearings 55 and 56 on the side of the machine frame. The shaft 54 it is to be understood extends parallel to the shaft 32.

The collar 53 carries a pin 57 adapted to engage a shoulder 58 provided on the inside of the cut out 52 in the yoke 48, so that when the shaft 54 and collar 53 are rotated to the left, as viewed 45 in Fig. 4, the pin 57 will engage the shoulder 58 and move the yoke 48 downwardly.

The shaft 32 supports a yoke 59 which is adapted to be rocked on the shaft 32 and which is held in the position shown in Fig. 4 by a spring-pressed 50 ball 60 engaging the side of the frame 1 of the machine. This member 59 carries pins 61 engaging a collar 62 slidably mounted on the shaft 15 of the feed roller 13 and non-rotatable with respect thereto so that as the upper end of the yoke 55

59 is rocked to the right, as viewed in Fig. 4, the collar 62 will be slid along the shaft 15 to bring the lugs 63 into engagement with the clutch lugs 64 on the side of the gear 37. To obtain the 5 rocking of the member 59 a pin 65 is carried by the member 48 and a pin 66 is attached to the yoke 59. These two pins are connected by a spring 68, which is normally under tension, and the pin 66 on downward movement of the member 48 is 10 adapted to be engaged by the extension 51 of the bracket 49 above referred to.

15 The shaft 15 of the feed roller 13 carries two steel discs 69 and 70 and an intermediate fiber disc 71. The discs 69 and 70 clamp the fiber disc 71 under the action of a spring 72. The disc 71 is provided with an arm 73 to which is attached one end of a spring 74 and the other end of the spring is anchored to any suitable part of the machine frame. The fiber disc 71 is adapted 20 to be moved between the stop pins 75 and 76. The function of this construction will be referred to hereinafter.

25 The fixed cutter bar 18 which cooperates with the movable cutter 43 is provided with a slot 79 at one end, and with a transverse slot 80 at the opposite end. The slot 79 receives a bushing 81 which has a depression in its upper face for receiving a screw 82 which passes down through the same and into the block 78 to which the bar is 30 attached. The slot 80 receives a bushing and screw 83. The screw 82 is eccentric to the bushing 81 so that by rotating the bushing the angle of the edge of the bar 18 with respect to the block 78 may be varied. The slot 80 permits the bar 18 to pivot when the cutter 43 is operating. The bar is backed by a spring actuated rod 84.

35 By this mounting of the bar 18 I am able to obtain a shearing action between the fixed and movable cutters without any flexing of either member.

40 The shaft 54 above referred to carries a collar 84 fixed thereto and between this collar and the bearing 56 the shaft is provided with a coil spring 85, one end of this spring being anchored to the collar 84 and the other end to the bearing 56, so that rotation of the collar 84 anti-clockwise, as viewed in Fig. 8, would place the spring 85 under tension. The collar 84 is provided with an operating handle or lever 86 and the outer end of the 45 collar is provided with a cam 87 adapted to cooperate with a cam 88 pinned to the shaft 54.

45 In operation the frame portions 14' are swung back to raise the rollers 12 and 19. The tape is pulled off the roll 3 and passed along the top of the lower roller 13. The frame members 14' are then swung down into closed position again as shown in Fig. 2 and latched by latches 91. The motor 29 is then energized to drive the shaft 32 and to effect rotation of gears 36, 38 and 40.

50 As above described the gear 36 meshes with a gear 37 loose on the shaft 15 of the feed roller 13. Consequently while the gear 37 is being rotated feed roller 13 is not yet started in operation. The gear 38 meshes with the gear 39 so that the lower feed roller 20 will be driven. The gear 40 is in mesh with the gear 41, as above pointed out, which is on the shaft 25 of the gluing roller 24 and hence the gluing roller will be driven. The shaft 25 on its end opposite the gear 41 carries a broad faced gear 92 which meshes with intermediate gear 93 driving a gear 94 in mesh with gear 95 on the shaft 27 for the glue roller 26.

55 96 is a doctor roller resiliently mounted adjacent the periphery of the glue roller 24 and the shaft carrying this doctor roller 96 carries a gear

97 which meshes with the broad faced gear 92, above referred to, so that this doctor roller will now be rotating.

10 If the hand lever 86 now be depressed the member 48 will be moved downwardly, the shaft 54 being rocked in an anti-clockwise direction, as viewed in Fig. 4, the pin 57 engaging the shoulder 58 on this member 48. This downward movement of the member 48 effects a pivoting upwardly of the cutter bar 42 against the spring 45. This same 15 downward movement of the member 48 carries the lateral extension 51 on the plate 49 into engagement with the pin 66 thereby pivoting the yoke 59 about the shaft 32, bringing the clutch lugs 63 into engagement with the lugs 64 on the side of the rotating gear 37. It will be noted that by reason of the pin 66 moving in an arc about the rod 32 while the pin 65 is moving in a straight line the spring 68 will be placed under greater tension.

20 The feed rollers 12 and 13, therefore, will now be driven, being geared together, and the paper will be advanced across the stationary cutter 18, the knife 43 being in raised position, between the upper and lower feed rollers 19 and 20, now being rotated, and over the face of the gluing roller 24. The paper is lifted from the face of this roller by the members 98. When the required amount of paper has been run through the lever 86 is further depressed, the cam 87 riding up the cam face on the collar 88 as indicated in Fig. 8 thereby forcing the shaft 54 endwise, i. e., to the left, as viewed in Fig. 3, to carry the extension 51 of the plate 49 out of the path of the pin 66. The spring 68 by the movement of the member 48, as hereinbefore mentioned, will be placed under greater tension and consequently when the extension 51 moves out of the path of the pin 66 this spring will restore the yoke 59 to its original position, disconnecting the clutch for the feed rollers 12 and 13.

30 As soon as the lever 86 is released the spring 85 will restore the lever to its original position and the spring 45 will snap the knife or cutter downwardly to shear the paper. The severed portion will of course be discharged from the machine, the rollers 19 and 20 still being rotated. The action of the spring 85 will carry the cam 87 to its original position with respect to the cam 88 so that the parts will be in position for the 35 next cycle of operation.

35 The friction between the fiber disc 71 and the steel plates 69 and 70 due to the spring 72 causes the disc to be rotated until its arm 73 strikes the stop 76, whereupon this friction is overcome by the drive of the feed rollers 12 and 13. As soon as 40 the clutch which constitutes part of the drive for the feed rollers 12 and 13 is disengaged, the spring 74 will reverse the fiber disc until its arm strikes the stop 75. Thus a slight reverse rotation of the feed rollers 12 and 13 is effected. The purpose of 45 this is to retract the end of the paper slightly from the cutting station to avoid any turning over of the leading edge of the paper due to the movement of the knife upwardly on the next operation of the machine.

50 It will be appreciated that the paper has not been glued at the time it is cut off, which is of advantage inasmuch as it keeps the knife from becoming coated with the glue or other adhesive employed.

55 It will be appreciated that the above operation is repeated as often and whenever desired, and that any length of paper may be fed before the cutting off operation is performed, this operation being manually controlled.

It will be appreciated also that by mounting the lower member of the cutting off mechanism as above described and by backing this member with the rod 84' which is under spring pressure the member 18 is permitted a slight pivotal action about the bushing 81, thereby providing a shearing between the movable blade 43 and the lower member 18 without the necessity of employing a flexible blade.

10 It is to be understood that changes may be made in the details of construction above described within the purview of my invention.

What I claim is:—

1. In a machine for handling paper tape, the combination of feeding means for advancing the tape, a vertically movable knife or cutter for severing the tape, means for raising said knife into operative position after each severing operation and means for reversing the feeding means after the tape is severed for retracting the leading end of the tape out of the path of said knife or cutter as the same is being raised into position ready for the succeeding severing operation.
2. In a machine for handling tape, the combination of tape advancing mechanism, a downwardly movable knife for severing said tape, driving mechanism for the advancing mechanism, a clutch intermediate the advancing mechanism and the driving mechanism, means operable substantially simultaneously for throwing out said clutch and releasing said knife for operation, means for raising the knife into operative position after each severing operation, and means for reversing the advancing mechanism after the tape has been severed by said knife prior to raising of the knife into position ready for the next severing operation to retract the leading end of the tape out of the path of the ascending knife.
3. In a machine for handling paper tape, tape advancing means, a drive therefor, a clutch intermediate the driving mechanism and the advancing mechanism, a second driven advancing mechanism spaced from the first-mentioned advancing mechanism, a knife intermediate said advancing mechanisms, means for throwing out said clutch to disconnect the first-mentioned advancing mechanism from the drive therefor substantially simultaneously with the operation of said knife, without interrupting the drive to the second-mentioned advancing mechanism.
4. In a machine for handling tape, the combination of a pair of feed rolls for advancing the tape, a drive therefor, a clutch intermediate the

drive and the rolls, a pivoted knife for severing the tape advanced by said rolls, a vertically movable yoke attached to said knife and operable to raise the same into operative position, a clutch operated by the movement of said yoke for clutching the driving means to the feed rolls, a rotatable shaft for imparting movement to said vertically movable member to elevate the knife and throw in said clutch, continued movement of said rotatable shaft releasing said member allowing the same to return to its original position, the knife to drop to sever the tape and to throw out said clutch.

drive and the rolls, a pivoted knife for severing the tape advanced by said rolls, a vertically movable yoke attached to said knife and operable to raise the same into operative position, a clutch operated by the movement of said yoke for clutching the driving means to the feed rolls, a rotatable shaft for imparting movement to said vertically movable member to elevate the knife and throw in said clutch, continued movement of said rotatable shaft releasing said member allowing the same to return to its original position, the knife to drop to sever the tape and to throw out said clutch.

5. In a machine for handling tape, the combination of intermittently operated feeding means for advancing the tape, a clutch rotated by said feeding means, tape severing means operating in timed relation to the operation of the feeding means, a spring fixed at one end and having its other end attached to a rotary part of said clutch to be placed under tension during operation of the feeding means to advance the tape, said spring retracting between operations of the feeding means to reverse the feeding means thereby to effect reversal of the movement of the tape.

6. In a machine for handling tape, the combination of tape feeding mechanism, a knife for severing the tape, means for raising the knife after a severing operation into position above the tape for the next severing operation, reversing means for the feeding mechanism operating automatically after the cutting operation to retract the tape out of the path of the knife on its upward movement to operative position.

7. In a machine for handling tape, the combination of tape feeding mechanism comprising a shaft, a disc clutch carried by said shaft, a spring attached to one of said discs, and to the machine frame, rotation of the shaft rotating one of said discs to place said spring under tension, a knife for severing the tape, said spring after the knife has descended to sever the tape reversing the tape out of the path of the knife when the latter ascends to operative position.

8. In a machine of the class described, the combination of a reciprocable knife, a relatively stationary knife or cutter cooperating therewith, an adjustable pivot about which the relatively stationary blade is adapted to be pivoted substantially at right angles to the travel of the reciprocable knife, and a spring opposing such pivotal movement.

JOSEPH ETTL.
